Faith, et al.; "Cable Connector"; U.S. Appl. No. 29/652,010, filed Oct. 19, 2018.

Primary Examiner — Barbara Fox

Assistant Examiner — Nathaniel D. Buckner

(74) *Attorney, Agent, or Firm* — Keating & Bennett, LLP

(57) **CLAIM**

The ornamental design for a cable connector, as shown and described.

DESCRIPTION

1. Cable Connector

1.1 is top, front, and right perspective view of a Cable Connector showing our design;

1.2 is a bottom, back, and left perspective view thereof;

1.3 is a top view thereof;

1.4 is a bottom view thereof;

1.5 is a back view thereof;

1.6 is a front view thereof;

1.7 is a left side view thereof;

1.8 is a right side view thereof; and

1.9 is a top, front, and right perspective view of the Cable Connector attached to a substrate.

(Continued)

The broken lines shown in the reproductions depict portions of the Cable Connector or environmental structure that form no part of the claimed design.

1 Claim, 7 Drawing Sheets
